CLAIM

The ornamental design for a candle with accoutrements, as shown and described.

DESCRIPTION

FIG. 1 is a front perspective view of a candle with accoutrements.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an exploded top perspective view thereof.

FIG. 9 is an exploded bottom perspective view thereof.

FIG. 10 is an exploded front elevation view thereof.

FIG. 11 is an exploded top plan view thereof; and,

FIG. 12 is an exploded bottom plan view thereof.

The oblique shading lines in the drawings are included to denote the transparent quality of surface planes on the candle with accoutrements. The broken lines shown in the drawings depict a portion of the candle with accoutrements that forms no part of the claimed design.
